UNITED STATES PATENT OFFICE

LELAND S. GOODWIN AND WILFRED A. MICHAUD, OF SALEM, MASSACHUSETTS

LEATHER-SPRAYING MACHINE

Application filed June 6, 1928. Serial No. 283,387.

The present invention relates to spraying machines, and has for its principal object to provide an apparatus of this character, adapted particularly for use in connection with the spraying of leather, hides, skins, and similar flat material.

A further object of the invention is to provide a series of spray nozzles disposed transversely of the work as the same is fed through the machine and connecting each of said nozzles with the blow in reservoir and an air hose arranged to eject the fluid under pressure from the nozzle upon the work.

A still further object is to provide a spray nozzle of novel construction in which the fluid is ejected therefrom angularly from the opposite side of the nozzle, in order that the fluid will spread over a considerable area and thus thoroughly cover the work.

A still further object is to provide an apparatus of this character of a simple and practical construction which is efficient and reliable in performance, relatively inexpensive to manufacture and maintain in operation, and otherwise well adapted to the purposes for which the same is intended.

Other objects and advantages reside in the special construction and combination of the various elements comprising the invention, reference being had to the accompanying drawings, forming a part hereof, wherein:

Figure 1 is a front elevational view with the housing of the apparatus removed, and with certain of the spray nozzles and supply pipes shown in section.

Figure 2 is an end elevational view.

Figure 3 is a similar view, showing the device encased in the housing provided therefor.

Figure 4 is a vertical sectional view through one of the spray nozzles.

Figure 5 is a transverse sectional view therethrough, taken substantially along the line 5—5 of Figure 4.

Figure 6 is a bottom plan view of one of the spray nozzles, and

Figure 7 is a view in elevation of the scrapper for the feed roller.

Referring now to the drawings in detail, the invention comprises a supporting frame com-

posed of a pair of spaced apart vertically extending frame members 5 having arms 6 extending from each side thereof and supported on legs 7.

Adjacent the lower portion of the frame and at each side thereof is arranged a pair of bearing brackets 8, within which a pair of spaced parallel shafts 9 are journaled for rotation, each of said shafts providing a mounting for a drum 10. The drums 10 are preferably of a reticulated construction having plates 11 arranged at each end thereof. Each of the drums 10 are connected for operation as a unit by a belt 12 of a width substantially equal to the length of the drum. Each of the shafts 9 extend outwardly from one side of the frame as shown at 13, the end of one of the shafts having a gear wheel 14 keyed thereon, and the ends of each of said shafts having sprocket wheels 15 likewise secured thereto. The sprocket wheels 15 are operatively connected with the chains 16, forming a positive drive connection for the drum. The end of one of the shafts also provides a mounting for a pair of drive pulley wheels 17. One of the pulley wheels is keyed to said shaft, with the other of said wheels freely mounted thereon, whereby to provide a means for the shifting of the drive belt for the purpose of throwing the drums into or out of operative engagement. A gear wheel 18 is operatively engaged with the gear 14, said gear wheel being keyed on a shaft 19 disposed in spaced parallel relation immediately above one of the drums 10 and journaled for rotation in bearing brackets 20 mounted at opposite sides of the frame.

Upon the shaft 19 is mounted a solid pressure roller 21 having its periphery disposed in close proximity with the surface of the belt 12. Disposed above the belt 12 and rearwardly of the roller 21 is a liquid feed pipe 22, extending transversely of the belt and supported at each end at the upper portion of the frame. Each end of the pipe 22, extending outwardly from the frame is provided with an elbow 23, providing a connection with a drain pipe 24, with a valve 25 interposed therein. Arranged about the pipe 22 is a jacket 26, having its walls in spaced relation

from said pipe, and connected at one end with a feed pipe 27, providing a connection with a supply of air under pressure. Extending upwardly from the feed pipe 22 and outwardly through the jacket is a supply pipe 28, communicating with a tank 29 mounted upon the frame and supported thereon by brackets 30. A valve 31 is interposed in said feed pipe controlling communication therethrough. Extending downwardly from the pipe 22, at spaced intervals throughout its length is a plurality of discharge pipes 32, having a nozzle 33, threaded in the lower end thereof. A sleeve 34 is disposed about each of the discharge pipes 32 with their respective walls in spaced relation, the upper end of the sleeve having communication with the interior of the jacket 26.

The lower end of the sleeve is closed with an annular plug 35 fitted between the walls of the discharge pipe and the sleeves and provided with a series of apertures 36 extending through said plug. The lower end of the sleeve 34 is externally threaded and adapted to threadably receive a cap 36' depending therefrom, the bottom portion of the cap having a seat 37 formed therein adapted for providing a snug fit for the tapered lower end 38 of the nozzle 33. Suitable adjustment for the end of the nozzle upon the seat is possible through the register attachment of the cap on the sleeve. The cap is secured in threadedly adjusted position by a set screw 39, extending through the wall of the cap and engaging the sleeve. A discharge opening 40 is formed at the center of the seat 37 providing a direct passage for the fluid from the end of the nozzle to the cap and by properly adjusting the tapered end of the nozzle with respect to the seat, a sufficient amount of air will be discharged through the opening 40, together with the liquid whereby to form a spray of the same.

As clearly illustrated in Figure 4 of the drawing, the bottom portion of the cap extends upwardly and inwardly in order to form the seat 37 and in said inclined portion is formed a pair of apertures 41 arranged at diametrically opposite sides from the nozzle and adjacent the sides of the frame. The apertures 41 thus constitute an air discharge port arranged to direct the air under pressure transversely of the flow of the liquid from the discharge nozzle and in addition to further breaking up the liquid to form the spray also serves to spread the spray thus formed at each side of the cap for increasing the area subjected to the spraying action. The drums and said spray nozzles together with their feed pipe are enclosed in the housings 42, having openings at the front and rear sides thereof and disposed substantially at a horizontal plane with the upper edges of the drum. Immediately beneath the said openings is supported a table 44, upon which

the strips of leather, hides or other material may be placed for feeding through the apparatus between one of the drums and the pressure roller 21. The belt 12 serves to convey the work through the apparatus beneath the spray nozzle for treatment thereby after which the same is fed from the housing at the rear thereof. Arranged immediately beneath the forward drum 10 is a scraper 45 engaging the belt 12 for cleaning the same before the belt comes into contact with the work.

The scraper 45 is attached at each end by adjusting screws 46 to brackets 47 secured to the frame 5. It will be apparent from the foregoing that a suitable liquid may be placed in the tank 29, such as for instance, a disinfectant for discharge from the nozzles 33 and through the action of the air discharged under pressure through the cap 36 will be sprayed over the entire surface of the work passing through the machine.

It is obvious that the invention is susceptible of various changes and modifications, without departing from the spirit or scope of the invention or sacrificing any of its advantages, and we accordingly claim all such forms of the device to which we are entitled.

Having thus described our invention, what we claim as new is:

A spray apparatus comprising a liquid spray pipe, a jacket for said spray pipe, a supply tank, a feed pipe extending from the spray pipe through said jacket for connection with the tank, a pipe connecting the jacket with a supply of air under pressure, a plurality of sleeves extending laterally from said jacket, discharge pipes communicating with the spray pipe and concentrically disposed in said sleeves, spray heads threaded to the ends of said sleeves and said discharge pipes having discharge orifices in each thereof disposed substantially in a common plane, the spray head for each of said sleeves having centrally and eccentrically disposed orifices, said central orifice having inwardly flared walls and said spray head for the corresponding discharge pipe having a tapered end complementary with the wall of said central orifice and an apertured spacing ring carried at the end of each of said discharge pipes for centering the tapered spray head in the corresponding central orifice.

In testimony whereof we affix our signatures.

LELAND S. GOODWIN.
WILFRED A. MICHAUD.
